CEILING STRUCTURE AND TILE THEREFOR
Lorien A. Carlson, Cloquet, Minn., assignor to Wood
Conversion Company, St. Paul, Minn., a corporation of
Delaware

Filed May 16, 1960, Ser. No. 29,535
10 Claims. (Cl. 20—4)

The present invention relates to tiled ceilings, to tile therefor, and mounting means for assembling tiles.

Tile ceilings conventionally display at the ceiling face a plurality of rectangular tiles, commonly squares, assembled edge to edge with no visible means of support. It is frequently necessary to remove a tile for effecting work behind it, and then to replace the removed tile without leaving a scar in the assembly.

The present invention provides a tile which can be readily assembled with others to form such a ceiling and which may be removed and replaced without leaving evidence of such removal. The invention, therefore, involves also the mounting means which is complementary to the tile.

In general, such ceilings are hung from a beyond-the-ceiling support, for convenience herein referred to as a roof. It is customary to provide a space between the roof and the tile ceiling for installing utilities, which may be electric conduits, water pipes, steam pipes, ventilating or air-conditioning ducts, and the like.

From the roof are hung a series of spaced parallel stringers defining a horizontal plane, for example, channels at four-foot intervals. To the channels are fastened crosswise thereof a series of parallel runners spaced apart a distance the same as one dimension of a rectangular panel to be assembled and carried by the runners. Various means or structures are available, when it is desired, to cooperate with various edges of the panels, and such means are best designed and constructed to facilitate assembling tile to form a ceiling.

By use of the structures of the present invention, a runner is used to mount a line of tile at aligned edges thereof in particular by relatively inserting a horizontal flange of a runner into a kerf in an edge of each tile. The series of hangers is so mounted that the said flanges thereof all point in the same direction, and the assembly of tiles proceeds in the direction.

After said first or kerfed edge of a tile or of tiles in a row is hung on such flange, the tile needs additional support to maintain it in a self-sustaining or substantially horizontal position, so that it may be eventually carried at its third edge, opposite said first edge, by the next forward runner.

According to this invention, the bulk of the tiles to be fixedly mounted at said first edge, will, when so mounted, form a sealed joint with the third edge of the adjacent tile. Said third edge of said adjacent tile which is presented to receive the first edge is free of the runner which eventually will carry it. The third edge of the rear tile has an undercut portion at the ceiling side leaving an overhanging flange portion. The first edge of the tile to receive the runner's flange has at the side of its flange-receiving kerf toward the exposed ceiling face of the tile an outwardly projecting flange fitting into said undercut portion for supporting said overhanging flange and sealing the joint, thus to carry the rear tile indirectly by the runner when not otherwise supported, as by the splines hereinafter described.

Although the said third edge of said rear tile may be supported by the hand of the operator until the two flanges overlap, the present invention avoids this by means having additional functions.

The second and fourth edges of each tile are square cut edges, each with a spline-receiving kerf below the

2

level of the flange-receiving kerf. The spline-receiving kerfs are so arranged that in an assembly of tiles the cross-section of the kerf is continuous lengthwise from tile to tile, and is extended crosswise from tile to tile by 5 opposing locations of kerfs in the second and fourth edges. The opposed kerfs provide a channel in which a spline may be slidably mounted. The spline has a length shorter than its spline-receiving kerf and a width such that it must lie in two opposing spline-receiving kerfs in 10 an assembled ceiling.

The lengthwise extent of a spline normally spans a joint between adjacent tiles, and it is slidable in the channel to free that joint to permit removal of a tile as later explained.

However, the splines have an additional function of initially supporting each last-installed tile mounted on a runner at its first edge and unmounted at its third edge, until a following tile is mounted at its first edge, whereby 15 to give final support.

20 Tiles are mounted by first forming a row or line of tiles joining the first and third edges, so that a completed row or fraction thereof presents at either the second or third edges a continuous length of spline-receiving kerfs. Into this length wide splines are inserted, so that half the 25 width of the spline is in kerfs and half projects. Each spline crosses the joint and lies in two adjacent tiles. As a result, there is a right angle of flanges to receive a tile in a row to follow, one leg of the right angle being that of a runner for receiving the first edge of a tile, and 30 the other leg of the right angle being aligned splines in aligned kerfs of the already mounted row or portion thereof.

Then a tile, designated A for reference, is fitted with its first edge onto the flange of a runner in position offset 35 laterally from final position to clear the said leg of half-splines and slightly lowered at its third edge to clear the runner at its third edge until in place on the runner's flange. Then it is leveled and shifted from said offset position to final position by movement to receive the 40 splines in its spline-receiving kerf. The tile A is thus held at its first edge and one of its two adjacent edges.

Then at the runner which lies ahead of its free third edge of tile A, the process is repeated and the projecting flange at the ceiling side of a newly mounted tile B, 45 supports said free third edge of tile A, giving three-edge support to tile A. Into the kerfs of the fourth edge of tiles A and B and those in line with them, are placed splines for supporting tiles in the following row.

By reason of the structure and arrangement above 50 described, the joints at the four edges of each tile are sealed against breathing and against any slight opening of a joint.

The invention may be carried out by structures shown in the accompanying drawings, in which:

55 FIG. 1 is a broken view in elevation of a single rectangular tile, taken on the line 1—1 of FIG. 2.

FIG. 2 is a side-elevation of the tile of FIG. 1 taken on the line 2—2 of FIG. 1.

FIG. 3 is a fragmentary view showing the righthand 60 edge of the tile of FIG. 1 with the metal support removed.

FIG. 4 is an enlarged view corresponding to FIG. 2 showing two tiles identical with the tile of FIG. 1 as they are joined at a support therefor.

FIG. 5 is a perspective view of a spline.

65 FIG. 6 is an enlarged cross-section of a spline taken on the line 6—6 of FIG. 5, showing its position in one tile in readiness to receive an adjacent tile, as illustrated in FIG. 7.

FIG. 7 is a perspective cut-away view of a portion 70 of an assembled ceiling showing the relationship of tiles, splines and runners.

FIGS. 1 to 3 show a tile suitable for the invention

above described. FIG. 1 is a plan view of the upper face 10 of a tile 11 showing a fragmentary length of a runner 12 with its vertical web 13 in cross-section and its horizontal flange 14 holding the tile.

The tile shown in FIG. 1 has in the clockwise direction, a first edge 15, second edge 16, third edge 17, and fourth edge 18. Edges 16 and 18 are square-cut edges. First edge 15 is rabbetted, with an upper edge face 15' and a lower edge face 15'' as the edge of a projecting flange 20. The third edge 17 is also rabbetted with an upper edge face 17' as the edge of an upper projecting flange 21, and a lower edge face 17'' complementary to edge 15'' in an assembly.

First edge 15 at face 15' is kerfed at 22 to receive runner flange 14, the kerf 22 being located above coplanar spline-receiving kerfs 23 and 24, respectively, in the second and fourth edges 16 and 18.

FIG. 4 shows in vertical elevation a fragment of an assembled ceiling at a joint, showing side edges 16 of two tiles, of which corresponding parts are identically numbered. The runner 12 is shown as a channel with an upper flange 12', by which it is mounted by means not shown, to a hanger suspended from a roof. The numeral 26 represents in cross-section a flat base of a spline 27 (FIG. 5) which has two stiffening ribs 28 upstanding on the same side of the base, shown with exaggerated thickness, and a hole 29 centered in each end 30 of the spline. The ribs have a height making the spline fit tightly in the kerfs 23 and 24.

Flange 21 is not wider than flange 20, and preferably is slightly shorter to provide clearance space 31 between edge face 17' and web 13.

Flange-receiving kerf 22 is above spline-receiving kerfs 23 and 24 so that splines may underlie flange 14 and be moved lengthwise across runner-flange 14. As a matter of convenience, kerf 22 lies immediately above kerfs 23 and 24.

FIG. 7 shows a cut-away portion of an assembled ceiling, with the parts numbered as described above. One point is to be noted. The left-hand spline has its base 26 down with ribs up. The right-hand spline is inverted with its base 26 up and ribs down. Thus, the ends 30 and 30' of adjacent splines may overlap in a common channel to permit one spline to slide over the other. By inserting a suitable and thin tool into a joint between adjoining side edges 16 and 17, and against the splines or ends of splines, or in holes in said ends, the four splines in a tile may be slid entirely out of the tile and into the adjacent tiles and superimposed on the splines in the adjacent tiles. Thus, the tile is freed from lateral support at the second and third edges and remains in place by its first edge enclosing a runner flange 14, and its third edge held up by an adjacent flange 20 underlying its own flange 21. As may be seen in FIG. 4, this third edge may be lifted so that the tile occupies dotted line position 11' and in such position the tile may be moved in the direction of arrow 32 and thereby pulled away from a flange 14 at its first edge. Thus, it is easily removed without moving adjacent tiles. It may be replaced by reversing the procedure, and sliding the splines back into place.

Although it is preferred that the third edge be supported by the flange 20, it is obvious that this support may be dispensed with, because the rigidity of the tile and the two splines in its edges provide sufficient support. However, this support exists only when the splines are in place. When they are slid out of a tile to remove it, the tile would drop except for the support by flange 20. Accordingly, the supporting flange 20 may be dispensed with, but with said resulting disadvantage.

The structure is such that each tile is sealed about its edges against breathing through the joint, the overlapping flanges 20 and 21, being effective at the edges 15 and 17, and the splines being effective at the edges 16 and 18.

The invention is not limited to the details of the illustrative embodiment shown in the drawings, and changes and modifications are contemplated as falling within the scope of the invention as set forth in the appended claims.

I claim:

1. A rectangular ceiling tile to be hung on horizontal runners in an assembly of a plurality of such tiles, said tile having a kerf lying in a first plane in a first edge and having a kerf in each of the two adjacent edges and in a common second plane, said planes being parallel to that face of the tile to be exposed when mounted in a ceiling, each of said kerfs in said second plane having at least a portion thereof located between the kerf in said first plane and said exposable ceiling face of the tile.

15 2. A tile according to claim 1 in which the kerf of the first edge is offset from the kerfs in the two adjacent edges.

20 3. A tile according to claim 1 in which the first edge has a flange projecting from the side of the kerf therein toward said exposable ceiling face with the lower face of the flange extending said exposable ceiling face of the tile, said flange having an upper face parallel with said exposable ceiling face, and in which the edge opposite said first edge has a projecting flange with a lower face in the plane of said upper face, the first-edge flange being at least as wide as the flange at said opposite edge.

25 4. A ceiling comprising a plurality of assembled rectangular tiles, a plurality of equally spaced parallel runners, and a plurality of splines, each runner having a vertical depending web and a terminal horizontal flange, said runners being mounted with said flanges extending in the same direction in a common plane, each tile having a first edge with a kerf therein containing a said flange, said kerf being in a first plane parallel to the exposable ceiling face of the tile, each tile having in each of its second and fourth edges adjacent said first edge a spline-receiving kerf in a common second plane parallel to said first plane and between said exposable ceiling face and said terminal flange, each spline being an elongated strip of metal capable of sliding in a spline-receiving kerf and along another spline in the same kerf, the length of the spline being not greater than the length of the spline-receiving kerf, each spline being positioned with its two ends in kerfs of adjacent joined tiles and its side edges in kerfs of adjacent joined tiles, said first edge of each tile having a first flange extending outwardly away from the opening of its kerf and below the said opening, the lower face of said flange extending said exposable ceiling face of the tile, and the upper face of said flange being parallel to said ceiling face, the third edge of each tile opposite said first edge having a second flange projecting therefrom with its lower face coplanar with the upper face of said first flange, said first flange being at least as wide as the second flange.

30 5. A ceiling comprising a plurality of assembled rectangular tiles, a plurality of spaced parallel runners, and a plurality of splines, each runner having a vertical depending web and a terminal horizontal flange, said runners being mounted with said flanges extending in the same direction in a common plane, each tile having a first edge with a kerf therein containing a said flange, said kerf being in a first plane parallel to the exposed ceiling face of the tile, each tile having in each of its second and fourth edges adjacent said first edge a spline-receiving kerf in a common second plane parallel to said first plane and between said exposed ceiling face and said terminal flange, whereby in joined second and fourth edges the kerfs thereof are coplanar and form a spline-receiving channel extending to adjacent tiles joined at their respective first and third edges, splines in said channels, each spline being an elongated strip of metal capable of sliding in a spline-receiving channel and along another spline in the same channel, the length of the spline being not greater than the length of the spline-receiving kerf

in a tile, each spline being positioned across the joint of first and third edges.

6. A rectangular ceiling tile having a body portion between two parallel planes defining a top face and an exposable ceiling face, said body having at a first edge a lowermost portion of the body extending as a first flange, and having at the opposite and third edge an uppermost portion of the body extending as a second flange, the first flange being at least as wide as the second flange, and the total thickness of the two flanges being not greater than the thickness of the body, the upper face of the first flange and the lower face of the second flange being coplanar, the second and fourth edges of the body being square-cut and having kerfs therein in a common plane parallel to said two planes, and said first edge above said first flange having a kerf therein parallel to said planes and above said two kerfs in the second and fourth edges.

7. A rectangular ceiling tile to be hung on horizontal runners in an assembly of a plurality of such tiles, said tile having a kerf therein with an upper kerf-face lying in a first plane in a first edge and having a kerf in each of the two adjacent edges and in a common second plane, said planes being parallel to the exposable ceiling face of said tile, each of said kerfs in said second plane having at least a portion thereof located between the lowermost portion of the kerf in said first edge and said exposable ceiling face.

8. A tile according to claim 7 in which the first edge has a flange projecting from the side of the kerf therein toward said exposable ceiling face with the lower face of the flange extending said ceiling face of the tile, and in which the edge opposite said first edge has a projecting flange having a thickness to overlie said first-edge flange when two such tiles are in coplanar relation with a first edge of one tile abutting the opposite edge of the second tile.

9. A ceiling comprising a plurality of assembled rectangular tiles, a plurality of equally spaced parallel runners, and a plurality of splines, each runner having a vertical depending web and a terminal horizontal flange, said runners being mounted with said flanges extending in the same direction in a common plane, each tile having a first edge with a kerf therein containing a said flange, said kerf having an upper face in a first plane parallel to the exposed ceiling face of the tile, each tile having in each of its second and fourth edges adjacent said first edge a spline-receiving kerf in a common second plane parallel to said first plane and between said exposed ceiling face and said terminal flange, each spline being

an elongated strip of metal capable of sliding in a spline-receiving kerf and along another spline in the same kerf, the length of the spline being not greater than the length of the spline-receiving kerf, each spline being positioned with its two ends in kerfs of adjacent joined tiles and its side edges in kerfs of adjacent joined tiles, said first edge of each tile having a first flange extending outwardly away from the opening of its kerf and below the said opening, the lower face of said flange extending the ceiling face of the tile, the third edge of each tile opposite said first edge having a second flange projecting therefrom and having a thickness and width to overlie said first edge flange when joined tiles are in abutting relation with the first edge of one tile against the opposite edge of the abutting tile.

10. A ceiling comprising a plurality of assembled rectangular tiles, a plurality of equally spaced parallel runners, and a plurality of splines, each runner having a vertical depending web and a terminal horizontal flange, said runners being mounted with said flanges extending in the same direction in a common plane, each tile having a first edge with a kerf therein containing a said flange, said kerf having an upper face in a first plane parallel to the exposed ceiling face of the tile, each tile having in each of its second and fourth edges adjacent said first edge a spline-receiving kerf in a common second plane parallel to said first plane and between said exposed ceiling face and said terminal flange, each spline being an elongated strip of metal capable of sliding in a spline-receiving kerf and along another spline in the same kerf, the length of the spline being not greater than the length of the spline-receiving kerf, each spline being positioned with its two ends in kerfs of adjacent joined tiles and its side edges in kerfs of adjacent joined tiles, the portions of the first edge and of the opposite and third edge being complementary for a closed joint at least at the regions below the splines, said complementary edges being at a separation distance the same as the spacing of the runners, and the portions of the first and third edges upwardly from the terminal flange being separated by a distance less than the spacing of the runners by an amount at least to accommodate the thickness of the vertical webs of the runners.
